UNITED STATES PATENT OFFICE.

RALPH W. ANTHONY, OF ELY, IOWA.

GAS-GRAVE.

1,354,531.

Specification of Letters Patent.

Patented Oct. 5, 1920.

Application filed December 1, 1919. Serial No. 341,640.

To all whom it may concern:

Be it known that I, RALPH W. ANTHONY, a citizen of the United States, residing at Ely, in the county of Linn and State of Iowa, have invented a new and useful Gas-Grate, of which the following is a specification.

This invention relates to improvements in grate attachments, and more particularly to an improvement upon my Patent No. 1,306,940, issued under date of June 17, 1919, in which there is provided an attachment for supplying gas to the grate for the purpose of starting a coal or wood fire without the use of kindling wood, and which attachment may be readily applied to any grate without change in the construction of the grate.

The invention contemplates an improved burner construction, whereby the same are prevented from clogging up with dirt and other foreign matter, and also, a novel connection with the source of gas supply.

With the above and other objects in view which will appear as the description proceeds, the invention resides in the combination and arrangement of parts and in the details of construction hereinafter described and claimed, it being understood that within the scope of what is claimed, changes in the precise embodiment of the invention shown can be made without departing from the spirit of the invention.

In the accompanying drawings:

Figure 1 is a plan view of a grate bar showing my improved attachment applied thereto, the grate bar being broken away at its ends;

Fig. 2 is a side view showing the attachment applied to a grate bar, the gas supply body being shown in section, and

Fig. 3 is an end view illustrating the device as shown in Figs. 1 and 2.

Referring to the drawings in detail, in which like reference characters designate corresponding parts throughout the several views, 5 designates a grate bar having the usual cross fingers 6 produced by projections or lugs extending from the sides thereof and upon which the fuel is supported. The grate bar is usually mounted at its ends in bearings in the stove or furnace, its front end projecting through the front wall of the fire box and formed to receive a suitable shaker handle for rocking the grate, or any

number thereof, which may be employed in connection with the particular heating unit.

The improved grate attachment forming the subject matter of the present invention, consists of the body iron elongated tubular body 7 which is U-shaped to fit contour of the grate bar 5, which latter is of substantially circular cross section, as indicated in Fig. 3 of the drawings. Thus, the body is provided with a concave recess in its top portion produced by a series of upwardly and outwardly projecting fingers or burners 8 in the form of hooks formed as integral parts of the casting of the tubular body or casting extending upwardly and outwardly between the projections or lugs 6 and intermediate of the top and bottom faces thereof. These burners are provided with openings 9 in the bottom portions thereof near their free ends, thus providing an overhanging shelf or top wall 10, to protect the burner and prevent foreign matter accumulating in the burner, in conjunction with the closed end portion 11 of the burner.

The body is secured in position by inverted U-shaped bolts or the like 12 which engage over the grate bar 5 between the projections 6 at suitably spaced points and engaged through opposed apertured ears 13 formed upon the body 7 or burner casting, nuts 14 being engaged on the threaded extremities of the bolts, in order to securely support the burner pipe or body in contact with the grate bar. The supply end of the body is closed and provided with an angular portion or elbow 15 to which is coupled as by a swiveled connection 16, an elbow 17 which in turn is provided with a swivel connection or coupling 18 with an elbow 19 to which the supply pipe 20 is coupled as indicated at 21. By this construction, the desired angular relation of the pipes may be provided, to accommodate the device to stoves or furnaces of different types of constructions and wherein the relation of the supply body to the grate must be varied, the said relation of the coupled elbows or pipe sections being such as to accommodate most any arrangement in use.

Thus, the gas may be supplied from a main under pressure and suitably controlled, so that igniting the burners 8, the flame will be caused to ignite the fuel upon the lugs or projections forming the fingers 6 that is, upon the grate and coal, wood or other fuel

may be started by this arrangement, quickly and economically without the use of kindling, and the usual trouble and annoyance of smoke, in starting fires. It should also be noticed that burners 8 are located below the top edges of the grate projections or lugs, instead of level with the upper surfaces thereof, thus obviating necessity or possibility of the same bearing the weight of the fuel as stated in my former patent, and also obviating the necessity of employing separate tubes since the burners are formed as an integral part of the casting forming the body or casting, the same projecting in parallel relation at either side of the grate bar. Also, since the casting or body is securely attached to the grate against rotation, and since the pipe connections are swiveled as specified, oscillation or shaking of the grate bar will be permitted without disturbing the gas connection, and without in any manner interfering with the usual cleaning of the grate or fire pot or box. However, it is to be understood that the joints or swiveled connection are made gas tight, suitable packing being employed if desired.

It is also to be understood that the burner body or conduit is to be cast to fit the grate bar, as specified being of cast iron or other suitable metal.

Having thus described the invention what I claim is:

1. A gas supply attachment for grates comprising a U-shaped body formed with integral oppositely and upwardly extending burners, said burners having their upper end portions closed, their outer ends closed and their lower portions adjacent the ends thereof provided with burner openings.

2. A gas supply attachment for grates comprising the combination with a grate bar having oppositely projecting fingers; of a burner casting fitted against the bottom of

the bar and having oppositely extending and outwardly projecting orificed burners providing concaved top recesses receiving the grate bar therein, said burners projecting between said fingers and below the top faces thereof, said burners being extended outwardly in hooked formation and having each a bottom opening and a shelf above said opening whereby to prevent access of dirt and foreign matter to the burner orifices, means for clamping said casting to the grate bar between said fingers, and swiveled supply connections leading to said casting.

3. A gas supply attachment for grate comprising the combination with a grate bar having oppositely projecting fingers; of a burner conduit fitted against the bottom of the bar and having oppositely extending and integrally formed orificed burners providing concaved top recesses receiving the grate bar therein, said burners projecting between said fingers and below the top faces thereof, said burners being extended outwardly in hooked formation and having each a bottom opening and a shelf above said opening whereby to prevent access of dirt and foreign matter to the burner orifices, means for clamping said conduit to the grate bar between said fingers, one end of said conduit being closed and the other end being provided with a depending elbow, and a series of angular pipe sections or elbows having swiveled connections with aforementioned elbows, and a pipe connection leading to one of said elbows and having connection with a source of supply for gas.

In testimony that I claim the foregoing as my own, I have hereto affixed my signature in the presence of two witnesses.

RALPH W. ANTHONY.
